[57] CLAIM

The ornamental design for a corner guard for furniture,
as shown and described.

DESCRIPTION

FIG. 1 is a perspective view of a corner guard showing
my new design;

FIG. 2 is a top plan view thereof;

FIG. 3 is a side edge view thereof;

FIG. 4 is a front edge view thereof;

FIG. 5 is a bottom plan view thereof.

The broken line fragment of a furniture top shown in FIG. 1 is for illustrative purposes only.
